UNITED STATES PATENT OFFICE.

HARRY C. ADAM, OF ST. LOUIS, MISSOURI.

SHADE OR LIGHT DIFFUSER FOR ELECTRIC SIDE-WALL FIXTURES.

Application filed March 31, 1924. Serial No. 703,164.

To all whom it may concern:

Be it known that I, HARRY C. ADAM, a citizen of the United States, residing at St. Louis, Missouri, have invented a certain new and useful Improvement in Shades or Light Diffusers for Electric Side-Wall Fixtures, of which the following is a full, clear, and exact description, such as will enable others skilled in the art to which it appertains to 10 make and use the same.

This invention relates to shades or light diffusers of the kind that are used with electric side wall lighting fixtures.

The main object of my present invention 15 is to provide a shade or diffuser for an electric side wall lighting fixture that will produce a brilliant light at a point under the fixture and also softly illuminate the space above, in front of and at the sides 20 of the fixture.

Another object is to provide a shade or light diffuser for an electric side wall fixture that will cause direct rays from the source of light to be projected downwardly 25 onto a table or desk positioned underneath the fixture, without liability of any of the direct rays being projected upwardly and outwardly into the room, thereby producing a side wall fixture shade that is particularly 30 adapted for use in hospitals, owing to the fact that it will supply ample light to a nurse's table over which it is arranged and at the same time illuminate the room in such 35 a way as to not be objectionable or harmful to the eyes of a patient lying in a bed that is located at such a point that the patient looks at or toward the fixture.

Another object is to provide a shade or light diffuser having the desirable characteristics above mentioned that is of neat and ornamental appearance, inexpensive to manufacture and of such construction that dust and insects cannot collect on the inside 40 of the same. Other objects and desirable features of my invention will be hereinafter 45 pointed out.

Figure 1 of the drawings is a side elevational view of my improved shade or light diffuser arranged in operative position on an electric side wall lighting fixture; and

Figure 2 is a bottom plan view of said shade.

Referring to the drawings which illustrate the preferred form of my invention, 50 A designates an electric side wall fixture that is equipped with a shade or light dif-

fuser constructed in accordance with my invention. Said shade comprises a translucent top part B, a translucent bottom part C, and a transparent part D so combined 60 and arranged that the major portion of the rays from the source of light α will pass through said translucent parts, and thus softly illuminate the space above, in front of and at the sides of the fixture and 65 some of the direct rays will strike against the inner side of said top part B and be projected downwardly from same through said transparent part D. The shape of the various parts of the fixture can be modified without departing from the spirit of 70 my invention, and said parts can be combined in various ways. I prefer, however, to construct the shade in one piece from glass or similar material so as to reduce the 75 cost of manufacturing same and produce a shade that has no openings through which insects and dust can enter and collect on the interior of the shade. In practice the top and bottom parts B and C of the shade are 80 formed of opal glass and the transparent part D of the shade is formed of crystal glass, but it is immaterial what kind of material is used to form the parts B, C and D of the shade, so long as the top part B 85 is constructed in such a way that it will break up the rays that are thrown upwardly and forwardly from the source of light α , the transparent part D will permit some of 90 the rays that strike against the inner surface of the top part B to escape downwardly so as to brightly illuminate the space directly underneath the shade and the bottom part C will break up the rays that are thrown forwardly and downwardly from 95 the source of light.

When the shade is designed for use with a one-light fixture, as herein illustrated, the top part B is made semi-ellipsoidal-shaped in general form and is so arranged 100 that it encases the upper half of the light bulb in the fixture and projects forwardly from same, the bottom part C is made so that it will encase the lower half of said bulb and be positioned at the rear of the 105 forwardly-projecting portion of the top part B and the transparent part D is disposed horizontally or substantially so so that it will serve as a closure for the portion 110 of the top part B that projects forwardly beyond the bottom part C. The inner end portion of the shade is cylindrical in gen-

eral form so that it can be inserted in a collar 1 on the fixture and retained therein by screws or other suitable devices 2 that project into an annular groove 3 in the 5 inner end portion of the shade.

While I have stated that the top part B of the fixture is semi-ellipsoidal-shaped in general form and that the transparent part D of the shade is disposed horizontally, I 10 wish it to be understood that my invention is not limited to a shade or light diffuser having parts of the particular shape and arrangement mentioned, or a shade that is designed for use with a one-light fixture. 15 The important thing is that the top part of the shade be constructed of translucent material or material having similar characteristics, and be of such shape that it will project forwardly beyond the source of light; 20 that the underside of the forwardly-projecting portion of the top part be closed by a transparent part that will not intercept the rays that are reflected downwardly by the forwardly-projecting portion of the top 25 part of the shade; and that the under portion of the shade which is located at the rear of said transparent part be of such construction that the downward rays from the source of light will be broken up effectively enough to produce a soft light. 30

If a shade of the construction above described is used with a side wall fixture that is positioned above a table or desk, the top of the desk will be brilliantly illuminated 35 by the direct rays that are projected downwardly through the transparent part D of the shade, and the space above, in front of and at the sides of the fixture will be softly illuminated by the rays which pass through 40 the translucent parts B and C of the shade. Accordingly, such a shade is particularly adapted for use in hospitals, because it will supply ample light to a nurse's table or desk arranged underneath the shade, without being 45 objectionable or injurious to the eyes of a patient lying in a bed positioned in the room at such a point that the patient looks at or towards the fixture. As the shade is constructed in one piece, it can be manufactured 50 at a low cost, and as there are no joints or openings in same through which insects and dust can pass, it is possible to keep the shade in a clean and sanitary condition by simply wiping off the dust that 55 accumulates on the exterior of same. While I have herein referred to the shade as a shade or light diffuser for electric side wall fixtures, I have defined the shade in this way merely to distinguish it from shades for 60 ceiling fixtures, for the shade is well adapted for use with desk lights, and in fact, any type or kind of light that is arranged or intended to be arranged in comparatively.

close proximity to a surface such as a desk or table which it is desired to brightly illuminate, one of the main distinguishing characteristics of my improved shade being that it will break up the major portion of the rays from the source of light with which it is used in such a manner as to softly illuminate a room and at the same time produce a brilliant light on a table or desk over which it is positioned. 65 70 75

Having thus described my invention, what I claim as new and desire to secure by Letters Patent is:

1. A shade or light diffuser for electric lighting fixtures of the kind mentioned, comprising a translucent top part of semi-ellipsoidal form in general outline that overhangs the source of light and projects forwardly beyond the same, a closure for the forwardly-projecting portion of said top part formed by a transparent part that is disposed horizontally or substantially so, 80 and a translucent bottom part arranged under the source of light at the rear of said transparent part and projecting downwardly below the same. 85

2. A shade or light diffuser for electric lighting fixtures of the kind mentioned, comprising a translucent top part of semi-ellipsoidal form in general outline, a closure 90 for the front portion of said top part constructed of clear glass or the like and disposed substantially horizontally, and a bottom part arranged at the rear of said closure and projecting downwardly below the same, said top part, closure and bottom part being integrally connected together. 95

3. A shade or light diffuser for electric lighting fixtures of the kind mentioned, comprising a translucent top part of semi-ellipsoidal shape in general outline, a translucent bottom part of less length than said top part arranged below the inner end portion of same and provided with a convexed front end, and a horizontally disposed transparent part that serves as a closure for the portion of said top part that projects forwardly beyond the front end of said bottom part. 100 105 110

4. A shade or light diffuser for electric lighting fixtures of the kind mentioned, comprising a one-piece member constructed of glass and provided with a bottom part that encases the lower half of a light bulb positioned in the fixture, a translucent top part that encases the upper half of said bulb and projects forwardly beyond the same, and a transparent part that serves as a closure for the forwardly-projecting portion of said top part and which is disposed horizontally or substantially so. 115 120
